(57) **CLAIM**

The ornamental design for a surgical nail for arthrodesis, as shown and described.

DESCRIPTION

FIG. 1 is a top, front perspective view of a surgical nail for arthrodesis, showing my new design;

FIG. 2 is a top plan view thereof, shown at an enlarged scale;

FIG. 3 is a bottom plan view thereof;

FIG. 4 is front elevational view of FIG. 1 thereof, whereas the rear elevational view is a mirror image; and,

FIG. 5 is a left side elevational view thereof; the right side elevational view is a mirror image.
